UNITED STATES PATENT OFFICE.

ARTHUR W. WARNER, OF MEDIA, PENNSYLVANIA, ASSIGNOR TO THE AMERICAN GAS COMPANY OF NEW JERSEY, OF CAMDEN, NEW JERSEY, A CORPORATION OF NEW JERSEY.

RETORT-STOKING APPARATUS.

1,401,295.

Specification of Letters Patent. Patented Dec. 27, 1921.

Application filed April 24, 1920. Serial No. 376,245.

To all whom it may concern:

Be it known that I, ARTHUR W. WARNER, a citizen of the United States of America, and resident of Media, in the county of 5 Delaware and State of Pennsylvania, have invented a certain new and useful Improvement in Retort-Stoking Apparatus, of which the following is a true and exact description, reference being had to the accompanying 10 drawings, which form a part thereof.

My invention relates to an apparatus designed to charge a coal gas retort with coal and to push out from the retort the coke of a former charge and the object of my invention 15 is to provide an apparatus of this sort which will occupy considerably less space in the gas-house than is required by apparatus heretofore employed for similar purposes and which will be adapted to charge the 20 retorts more efficiently and with better disposal of the coal in the retorts than has heretofore been found practical. The leading features of my invention consist in my employment of a horizontal sprocket wheel in 25 combination with a push bar formed of links and adapted to wind upon the horizontal sprocket wheel and when the links are straightened out to so interengage with each other as to form a self-supporting and fairly 30 stiff bar to the bottom side of which the flights are pivotally supported.

The nature and detail of my improvements will be best understood as described in connection with the drawings in which they 35 are illustrated and in which—

Figure 1 is a side elevation of an apparatus embodying my improvements and with the push bar shown as fully entered into a retort.

40 Fig. 2 is a plan view of the apparatus shown in Fig. 1.

Fig. 3 a sectional view taken as on the line 3—3 of Fig. 1 and shown on an enlarged scale.

45 Fig. 4 is a view showing a portion of a retort in vertical section and a portion of the push bar and flights with the coal being stoked into the retort, shown in the position it occupies during the stoking operation.

50 Fig. 5 is a similar view with the push bar in process of retraction showing the coal in the form in which it is left after the withdrawal of the push bar.

Fig. 6 is a cross sectional view of the line 55 6—6 of Fig. 5.

Fig. 7 is a horizontal sectional view taken through the center of a portion of these links of the push bar which are adapted to be wound upon the sprocket.

Fig. 8 is a side view of one of the links 60 of which the push bar is made up.

Fig. 9 being a cross section on the line 9—9 of Fig. 8 and

Fig. 10 a cross section on the line 10—10 of Fig. 8. 65

Fig. 11 is a side view of one of another series of links entering into the composition of the push bar.

Fig. 12 being a cross section on the line 12—12 of Fig. 11 and

Fig. 13 a cross section on the line 13—13 of Fig. 11. 70

A, Fig. 1, is a car supported by wheels B, B, traveling on tracks B' B' and supporting a series of screws A' A', etc. which are 75 geared to rotate simultaneously. As shown, two of the screws have attached to their upper ends gear wheels A² and A³ and the other two of the screws have attached to their upper ends gear wheels A⁴. A shaft, 80 A⁵, is rotated through a worm wheel A⁶ by a motor indicated at C and has at its ends gear wheels A⁷ A⁸ in engagement with the gears A² A³. A pair of shafts A⁹ A¹⁰ carried by the car A have on their ends gears A⁹, 85 A¹⁰ respectively, engaged with the gears A³ and A⁴. D is a platform supported on ends indicated at D' D' through which pass the screws A' A' so that as the screws are rotated the platform is raised or lowered. E 90 is a shaft vertically supported on the platform D, having secured to its lower end a worm wheel E' in engagement with a worm E² driven by a motor indicated at E³ and to the upper end of the shaft is secured the 95 horizontal sprocket wheel indicated at F; F' F' indicating the sprockets extending out from the edge of the sprocket wheel. G, G, are horizontal guide ways secured on the platform D. G' is a bracket secured to the 100 platform and carrying at its upper end a push bar guide indicated at G². G⁴ is a similar bracket carrying at its upper end the similar push bar guide indicated at G⁵, the form of which is best shown in Fig. 3. 105 G³ G³ are brackets secured to the platform D and supporting the hopper indicated at H, the form of which is best shown in Fig. 3, H' indicating its rear edge and H² its forward edge which regulates the height of 110

the coal pushed under it into the retorts. In order to provide for an adjustment on the front edge of the hopper I have shown plates indicated at H^3 H^3 pivoted to the front of the hopper at H^4 and held in any desired position as by clamping screws H^5 H^5 . I have indicated at H^6 rearwardly extending wings forming part of the hopper and extending back beyond the edge H' which are advisable for the proper feed of coal from the hopper into the trough. I , I , are trough supporting legs guided by and movable along the guide ways G , G , and supporting the trough indicated at I' which is shown in retracted position in Fig. 2, and in position for use in charging a retort in Fig. 1. J indicates a retort which may be of any usual construction and built into a stack in the usual way. K is a guide bar advantageously used to properly guide and aline the links of the push bar as they pass from engagement with the sprocket wheel. L is a bar or link forming the end of the push bar and of greater length than the other links of which the push bar is made up. This link, L , does not wind up upon the sprocket wheel. The remaining links of the push bar are made up of two series of links indicated at L' and L^2 and these links are to be so pivotally connected with link L and with each other that they will wind up on the sprocket wheel and when, by a reversed movement of the sprocket, they are unwound from it they will form a push bar, the component links of which will so interengage with each other as to form a stiff, self-supporting bar which can be projected into a retort without coming in contact and being supported by the bottom of the retort. As shown, and, as I prefer to construct the push bar, the larger links L' are formed with pivot pin holes M near but not at the center and with pivot pin holes M' at the end more distant from the pivot pin hole M . On each side of the pivot pin hole M the link is a U shape with the openings, however, turned in different directions as indicated at M^2 and M^3 and along the bottom of each U is formed a guide groove indicated at M^4 and M^5 . The smaller links L^2 , shown in detail in Figs. 11, 12 and 13, are generally similar in construction, the approximately central pin hole being indicated at N and the end pin hole at N' . The guide grooves are indicated at N^4 and N^5 and the hollow U 's at N^2 and N^3 and it will be understood that when the links are pivoted together as by pins O , O , (see Fig. 7) the ends of the link L^2 when the links are straightened out lie within the U 's M^2 and M^3 of the links L' and it will readily be understood that by this construction the links are so interengaged with each other that a very stiff, self-supporting push bar is formed from them. O' O' indicate

rollers on the pins O , O , the diameters of these rollers being such that their edges will come flush with or preferably somewhat beyond the bottom of the guide grooves in the links. P , P , etc., are the flights which are pivotally supported on the bottom of the links of the push bar, the flights being cut out at their central upper edge as indicated at P' and having ears P^2 P^2 turned back and engaged by a pivot bolt Q^2 which is supported by a bracket Q secured to the under side of the links of the push bar and provided with stops Q' which prevent the flights from turning backward beyond an approximately vertical position as indicated in Fig. 4, while permitting them to turn freely backward into the position indicated in Fig. 5.

The guideways formed in the link or bar L and correseponding to the guide-ways formed on the sides of the links L' and L^2 are indicated at l , l , and at R I have indicated a thin plate secured to the top of the link L and intended to protect it against the heat of the retorts.

To return to the flights P I have indicated in Fig. 3 by dotted lines and the symbol p' that the opening P' may be made deeper and I would note in this connection that some opening at this point is very desirable if not necessary in order to prevent coal getting in between the flight and the bottom of the push bar and preventing the flight from turning upward to the desired position when the push bar is retracted. The lateral edges of the flights P are rearwardly curved as indicated at P^3 so that when turned backward to the position, for instance, shown in Fig. 5 they will clear the sides of the retort.

When moving from place to place the push bar is retracted as shown in Fig. 2 and the trough I' is also retracted. The platform D being shifted to proper registered position with a retort, the trough I' is moved into registry with the retort, as shown in Fig. 1, a charge of coal is fed into the hopper and the sprocket wheel is revolved in a clockwise direction unwinding the links of the push bar and pushing them through the trough into the retort. As the links of the push bar move forward they are properly alined and supported by the guides G^2 and G^5 the latter support affording the last supporting device for the push bar as it passes into the retort. The coal going from the hopper into the trough is pushed through the trough and into the retort and in the retort takes approximately the position in front of and behind the flight indicated in Fig. 4 and when the retort is fully charged the sprocket is revolved in the opposite direction retracting the push bar and flights, the flights moving upward to the position indicated in Fig. 5 and performing the very important function of leveling off the coal in the retort as indicated in Figs. 5 and 6; the contour of the top

of the coal pile as indicated in Fig. 6 being that most desirable for good coking operation.

It will be understood that my invention is not dependent upon the character of the apparatus used for supporting and adjusting the position of the push bar and its mechanism and also that while I have illustrated my invention in what I believe to be its best and most efficient form my claims are not to be understood as specifically limited to the illustrated construction except where such limitation is clearly expressed in the claims.

Having now described my invention, what I claim as new and desire to secure by Letters Patent, is:

1. In an apparatus of the class described a horizontal sprocket wheel in combination with a push bar made up of links connected by vertical pivots and adapted to wind on the sprocket wheel.
2. In an apparatus of the class described a horizontal sprocket wheel in combination with a push bar made up of links connected by vertical pivots and adapted to wind on the sprocket wheel and to interengage with each other when straightened out to form a bar of considerable rigidity.
3. In an apparatus of the class described a horizontal sprocket wheel in connection with a push bar made up of links connected by vertical pivots and adapted to wind on the sprocket wheel and to interengage with each other, when straightened out to form a bar of considerable rigidity, and a series of flights pivotally supported on the lower sides of the links so as to turn up against the

links when the push bar is retracted after charging a retort.

4. In an apparatus of the class described a horizontal sprocket wheel in combination with a push bar made up of links connected by vertical pivots and adapted to wind on the sprocket wheel and to interengage with each other, when straightened out to form a bar of considerable rigidity, and a series of flights pivotally supported on the lower sides of the links so as to turn up against the links when the push bar is retracted after charging a retort, said flights being formed with rearwardly curved lateral edges.

5. In an apparatus of the class described a horizontal sprocket wheel in combination with a push bar made up of links connected by vertical pivots and adapted to wind on the sprocket wheel and to interengage with each other, when straightened out to form a bar of considerable rigidity and a supporting guide arranged to hold the push bar in proper position in front of a retort.

6. In an apparatus of the class described a platform adjustable in position to register with any of a series of retorts, in combination with a horizontal sprocket wheel supported on said platform, a push bar made up of a series of links connected by vertical pivots and adapted to wind on the sprocket and so interengaged when straightened out as to form a self-supporting bar, a trough adjustable on the platform to form a conduit to a retort and a hopper for feeding coal to said trough.

ARTHUR W. WARNER.
